UNITED STATES PATENT OFFICE.

GIULIO MARCHETTI, OF HALIFAX, COUNTY OF YORK, ENGLAND, ASSIGNOR
TO JOHN CROSSLEY & SONS, OF NEW YORK, N. Y.

DESIGN FOR A CHAIR-COVER.

SPECIFICATION forming part of Design No. 18,682, dated October 9, 1888.

Application filed September 13, 1888. Serial No. 285,320. Term of patent 3½ years.

To all whom it may concern:

Be it known that I, GIULIO MARCHETTI, of Halifax, York county, England, have invented a certain new and original Design for 5 Chair Covers; and I do hereby declare the following to be a full, clear, and exact description of the same, such as will enable those skilled in the art to which it appertains to make and use the design, reference being had 10 to the accompanying photograph, which forms part of this specification.

My invention relates to a design for chair-covers; and it consists in a novel ornamentation of the filling or body of the chair cover 15 and the border surrounding the same, substantially as hereinafter described, and pointed out in the claim.

The accompanying photograph is a plan view 20 of a chair-cover embodying my design. A represents the filling or body design of the chair-cover, consisting of an all-over or equally-distributed effect composed of small

Indian stems, leaves, branches, and blossoms conventionally treated. At the head of said filling are two triangular panels, B B. The 25 filling design of said panels is of Indian work, representing small stems and blossoms conventional in character. Surrounding said body or filling A are an inner border, C, and an outer border, D. The character of both borders is Indian harmonizing with the filling. The inner border, C, is of very fine branch-work, with leaves and blossoms, which, like the rest of the cover, is conventional, while the outer band, D, or border consists of a continuous scroll somewhat more ornamental in character. 30 35

I claim—

The design for chair-covers represented in the accompanying photograph.

GIULIO MARCHETTI.
